UNITED STATES PATENT OFFICE.

LOUIS R. MENDELSON, OF CLEVELAND, OHIO.

INDIRECT WATER HEATER.

Application filed July 22, 1921. Serial No. 486,727.

This invention relates to indirect water heaters, such as are used in connection with steam, hot water, or vapour heating plants for the purpose of heating water for household or other uses

The objects of the invention are to provide an improved device of the kind described which is cheap to manufacture and install, which is highly efficient and which 10 positively separates the two currents of water to be heated and the heating medium therefore without leakage of one to the other or to the outside of the indirect heater.

Further objects of the invention are in 15 part obvious and in part will appear more in detail hereinafter.

In the drawings, which represent one suitable embodiment of the invention, Fig. 1 is a diagrammatic view illustrating a heating 20 system with the indirect heater installed therein; Fig. 2 is a sectional elevation, on a larger scale, through the indirect heater; and Fig. 3 is a sectional plan view on the line 3—3, Fig. 2.

25 In the drawings, 1 represents a suitable household furnace, which may be either a hot water, steam or vapour boiler, but in any case is provided with a reservoir 2 for the heating medium to be circulated to the various 30 rooms for heating purposes. In the present instance it will be assumed that this heating medium is hot water. 3 represents the usual hot water tank for holding hot water for domestic purposes, which may be located adjacent the furnace, as shown, or in the 35 kitchen or at any other suitable place. Said tank has a cold water supply pipe 4 and a service pipe 5 for conducting hot water to the place of use. 6 is the usual gas or oil 40 heater for heating the water in tank 3, the water being circulated between tank 3 and heater 6 by pipes 7.

The indirect heater forming the subject matter of this invention is indicated at 10 45 and is shown in detail in Figs. 2 and 3. It comprises a hollow casing 11 divided horizontally for convenience in assembly, the two halves each having integral end head and cylindrical wall portions, the latter being flanged at 12 and held together with a suitable gasket 13 by the bolts 14. The chamber 15 within said casing communicates by pipes 16 with the chamber 2 of the furnace so that heating medium, such as hot 50 water, is circulated from the furnace through the indirect heater. The flow may be shut 55

off by suitable valves 17. Jacket 11 may be made of any suitable cheap material, such as cast iron.

Within the chamber 15 are located one or 60 more coils 18, one being shown, through which the water from tank 3 is circulated for heating the same. This coil is usually of copper, although any suitable material may be used. At each end said coil has brazed 65 or otherwise secured thereto a fitting 19 which for a short distance continues the spirality of the coil, then extends inwardly to and along the axis of the coil and out through an opening in the casing head. 70 Within the casing each fitting is provided with a non-circular portion 20, say hexagonal or square, which lies between lugs 21 of the casing to prevent its rotation. Lead gaskets 22 are placed around said fitting inside 75 and outside of the casing, the casing surfaces which receive them being faced off smooth if necessary. A lock nut 23 is screwed up on the threaded end of the fitting to secure and seal all joints and the outer end of each fitting has connected thereto a pipe 24 communicating with the water tank 3.

In summer or when the furnace 1 is not in use the water in tank 3 is heated with the 80 heater 6. However, when there is a fire in 85 furnace 1 the heating medium therefrom is circulated downwardly through the chamber 15 of the indirect heater and heats the rising stream of water in the coil 18, so that the furnace, by heat exchange, heats the 90 water in tank 3.

The indirect heater avoids the use of coils in the furnace and does away with burning out or rusting such coils and the joints thereto. The heater may be made at low cost 95 and is easily and cheaply installed. It also is so arranged as to secure high efficiency and avoids any possibility of leakage. In assembling the parts, the coil is secured at one end in one half of the casing or jacket, 100 the other half of the casing is then secured in place, and finally the coil is secured to the second half of the casing. No harmful strain is placed on the coils and expansion and contraction have no bad effects.

105 What I claim is:

1. An indirect water heater, comprising a casing having side and end wall portions, connections for circulating a heating medium through the casing, a coil in said casing through which liquid to be heated may 110 be circulated, each of the two end wall por-

- tions of said casing having associated therewith one of the end portions of said coil, means for securing the coil in place, and means arranged within said casing and acting independently of said securing means for preventing relative rotary movement of said coil and said casing.
2. An indirect water heater, comprising a casing, having side and end wall portions, 10 connections for circulating a heating medium through the casing, a coil in said casing through which liquid to be heated may be circulated, each of the two end wall portions of said casing having associated therewith one of the end portions of said coil, means for securing the coil in place, and means additional to said securing means for preventing relative rotary movement of said coil and said casing while assembling 15 and disassembling said parts.
3. An indirect water heater, comprising a hollow cylindrical casing divided transversely between its ends into two parts, each having integral end head and cylindrical 20 wall portions, means for securing the cylindrical wall portions of the two parts to each other, side connections through the wall portions for circulating heating medium through the casing, a coil in said casing 25 through which liquid to be heated may be circulated, said coil at each end extending 30
- through an end head of the casing, means for securing the coil in place, and additional means for preventing relative rotation between the coil and casing. 35
4. An indirect water heater, comprising a two part hollow casing provided with means for securing the two parts to each other, connections for circulating heating medium 40 through the casing, a coil in said casing through which liquid to be heated may be circulated, said coil within the casing being provided with a non-circular portion, means on the casing for engaging said portion, a gasket surrounding the coil and engaging the casing, and a nut for securing the parts together. 45
5. An indirect water heater, comprising a casing having side and end wall portions, 50 connections for circulating a heating medium through the casing, a coil in said casing through which liquid to be heated may be circulated each of the two end wall portions of said casing having associated therewith one of the end portions of said coil, means 55 for securing the coil in place, and means integral with said coil and said casing end portions for preventing relative rotary movement of said coil and said casing. 60

In testimony whereof I hereby affix my signature.

LOUIS R. MENDELSON.
